(57) **CLAIM**

We claim the ornamental design for the prefilled syringe dispensing device, as shown and described.

DESCRIPTION

FIG. 1 is a perspective view from the top front of the claimed design;

FIG. 2 is a perspective view thereof from the bottom rear;

FIG. 3 is a top plan view thereof;

FIG. 4 is a front elevation view thereof;

FIG. 5 is a side elevation view thereof;

FIG. 6 is a rear elevation view thereof;

FIG. 7 is a side elevation view thereof; and,

FIG. 8 is a bottom plan view thereof.

The features shown in broken lines depict environmental subject matter only and form no part of the claimed design.
